UNITED STATES PATENT OFFICE.

WILLIAM E. FOWLER, SR., OF CHICAGO, ILLINOIS, ASSIGNOR TO THE FOWLER CAR COMPANY, OF CHICAGO, ILLINOIS, A CORPORATION OF ILLINOIS.

STEEL-SHEATHED BOX-CAR.

1,151,351.

Specification of Letters Patent. Patented Aug. 24, 1915.

Application filed May 28, 1914. Serial No. 841,465.

To all whom it may concern:

Be it known that I, WILLIAM E. FOWLER, Sr., a citizen of the United States, and resident of Chicago, in the county of Cook and 5 State of Illinois, have invented certain new and useful Improvements in Steel-Sheathed Box-Cars, of which the following is a specification.

My invention relates to railway cars and 10 has particular reference to a novel steel-sheathed box car.

An object in the present construction is to provide a car of steel exterior, and, if desired, with a wooden interior, for the purpose 15 of insulation which shall be so constructed as shall obviate the necessity for framing, the load being carried by the walls themselves.

A further object is to provide means in 20 connection with such a car whereby a wooden sheathing may be readily applied if desired, the interior surface including side and end walls, floor and roof, being adaptable to the application or omission of the 25 wooden sheathing element.

For many uses a car composed of a single steel sheathing would be satisfactory but such cars are not available for general service unless provision is made for the attachment 30 to the interior of bracing for securing certain types of lading. Such bracing cannot be readily secured without the provision of wooden posts to which the bracing would be nailed. Such posts or nail- 35 ing strips are particularly desirable in the floor as well as in the walls and roof.

The car which I have devised is of exceeding simple construction and may consist in a plurality of metallic units or sheets bent 40 at their edges to facilitate fastening, the point of juncture of the plates accommodating a wooden post which may assist in bracing the sides and provide for the attachment of an inside sheathing of wood by means of 45 nails. The same construction is followed in the floor the wooden strips being seated flush with the metallic floor. In the roof the same principle of construction is followed a notable advantage being gained in the omission 50 of the usual carlines and purlines. The joints in the metallic members serve as the roof braces or carlines.

A particular advantage in the construction here presented is in that a dead air space

is provided between the metallic and non-metallic sheathing. This is accomplished by permitting the wooden posts which are seated in the metallic sheathing to project inwardly beyond the faces thereof for a short distance. When the wooden sheathing 60 is nailed thereto a dead air space remains. This acts as an efficient insulator from heat and cold.

Preferably the wooden posts are secured in the channels formed at the juncture of the 65 side plates by means of bolts or rivets which extend in a line parallel with the plane of the plates. Thus the tendency of the channels to open up under strain is overcome. The sides should not be relied upon to carry the 70 load without this provision inasmuch as the strength of the plates against elongation would only be the elastic limit of the metal forming the channel.

The invention will be more readily understood by reference to the accompanying drawings, wherein,

Figure 1 is a side elevation of a portion of a car side constructed in accordance with my invention; Fig. 2 is a transverse vertical 80 section through the construction shown in Fig. 1; Fig. 3 is a longitudinal section through a portion of the car body; Fig. 4 is a similar view of the end construction; Fig. 5 is an enlarged detail of the method of 85 joining the roof structure to the side wall; Fig. 6 is a similar view taken at a point adjacent to that shown in Fig. 5; Figs. 7 and 8 are enlarged sections of the construction shown in Fig. 3; Fig. 9 is an end view of 90 the casting by means of which the roof structure is secured to the wall at the point of the usual carline. Figs. 10 and 11 are sectional views of a modified form of top and bottom connections for the side wall, and, 95 Fig. 12 is a view similar to Fig. 7, showing a modified construction.

Referring more particularly to the drawings it will be seen that on an under frame consisting of center sills 10, and transoms 100 11, I superpose my novel box arrangement, the side and end walls of which may consist in sheets or plates 13, preferably flanged at their four edges. The bottom flanges 14, project outwardly and rest within a notch 105 12, formed in the transoms 11. As shown in Fig. 1, the bottom flanges of adjacent sheets are over-lapped as at 15, the joint

being fixed at a point removed from the vertical joint between the sections. The reason for this is that the flange at one side of the sheet is permitted to extend to the full width 5 of the material prior to the formation of the side joint or connection between adjacent sheets whereas a small portion of the flange of the sheet in the adjacent section is removed. As best shown in Fig. 7, the side 10 connections between adjacent sheets is made by bending the marginal edges of the sheets in the form of an angle 16, then over-lapping the edges 17, 18 of the angles, and joining the same by means of rivets 19. I 15 may prefer to bend the marginal edges of the plates in the form of channels 20, as best shown in Fig. 12, seating one channel within the other and holding the same in proper relation by means of the rivets 21.

20 As an additional stiffening means I may prefer to provide intermediate vertical crimps 22, in the plates these being formed without cutting the sheets except at the bottom where the flanged portion is cut out as required 25 and over-lapped as at 23. At the tops the sheets are flanged outwardly as shown in Figs. 5 and 6, this flange 24^a serving to strengthen the sheet and provide means for the attachment of the roof structure, or the 30 flange may be omitted and the sheet strengthened by means of the angle 24, as shown in Fig. 10, extending from end to end of the car. The flange gussets 25, are riveted either to the angle 24, or the integral 35 flange 24^a, the gussets also being riveted or bolted through the joints of the sheets. At the corners of the car the side sheets are bent into the usual angular shape whereas the end sheets are bent into channel form 40 as at 26, the legs of the angle and channel over-lapping and being secured together by rivets 27.

The floor construction is very similar to that of the side walls. The sheets 28, extend longitudinally of the car their outer edges 45 29, resting on the angles 29^a, and being riveted thereto. The joints 30, in the floor plates are similar to the side joints and I may also provide channels or crimps 31, in 50 the plates as shown. The floor plates may also be riveted directly to the center sills as shown at 32.

The roof construction consists in a similar 55 series of plates 33, the joints in the roof being preferably of the form shown in Fig. 12; that is, the marginal edges of the roof plates being formed into channels, one channel being seated within another. The joints of the roof plates are secured at the eaves 60 to a casting 34, having inwardly projecting flanges 35, which fit snugly within the channels of the joints and which is provided with a vertical wall terminating in a depending flange 36, secured to the down- 65 turned edge 37, of the roof sheets. These

castings 34, are riveted as at 38, to the flanges 24^a, at the upper edge of the sheets. Additional rivets 39, are provided which pass through the channel joints and the casting 34. Thus the roof sheets are securely fastened to the side wall. Short angles 40, are riveted to the channel joints at the peak of the roof and a running board 41, is secured to the angles. A channel-shaped ridge pole 42, is secured to the metal 70 work inside of the car, as best shown in Fig. 2.

The description thus far has been of the metal work composing the car without relation to the provision for wooden fillers 80 or insulation. Within each of the channels formed in the side and end walls at the joints and intermediately of the joints, I prefer to locate posts 43, and secure the same in place by means of bolts 44, passing transversely through the posts and the angles at the edges of the sheets in a line parallel with the car side. If a post becomes broken or deteriorates it may readily be removed and replaced by removing the 90 bolts. Wood timbers or nailing strips 45, are provided for the floor members and are located in the channels formed at the intersection of the sheets. A similar construction is followed for the roof. In the case 95 of the roof, of course, the wooden filler members 46, are curved to correspond to the curvature of the roof. Bolts 47, may be used to secure the joints in the roof structure. To all of these wooden posts or 100 fillers an inside sheathing 48, may be nailed or otherwise secured, the construction being such that a dead air space 49, is left between the sheathing both as to the side and end walls. As best shown in Fig. 6, a 105 similar space 50, is left between the roof sheets and a wooden lining 51, in the roof. This insulating space is secured by allowing the posts or filler blocks 43, 46, to project outside the plane of the metal sheets the 110 required distance. This is clearly shown in Figs. 6, 7 and 8. In case no inside sheathing is desired the posts or filler blocks may be installed with their edges flush with the 115 surface of the metal sheets, and when bracing is required within the car the wooden posts are available for the attachment thereof.

In the modified construction shown in Fig. 11, a Z-bar side sill 14^a, is provided 120 which extends from end to end of the car. In the event such construction is followed the flange 14, on the bottom of each sheet is omitted. Otherwise the side construction is unchanged.

While I have shown the inside sheathing as being nailed to the wooden fillers it is obvious it may be secured in any other manner. Also the roof sheathing may be secured by wedging action in view of the 125 130

inclination or curvature of the roof. These and other modifications I consider within the scope of my invention.

I claim:

5. 1. In a railway car, the combination of underframing, a superposed box, said box including walls composed of metallic sheets having their vertical marginal edges bent outwardly into angular form, portions of 10 the edges of adjacent sheets being overlapped and providing a vertical recess, a wooden post mounted in said recess and securing means passing through said wood and metallic members, said securing means 15 extending in a plane parallel to the sheets composing the wall, said recess and post being located so as to provide a plane interior surface for said car substantially as described.
  20. 2. In a railway car, the combination of underframing, side walls superposed thereon, said walls being composed of overlapped metallic sheets providing vertically extending recesses, wood posts mounted in said recesses and fastening means extending through said posts and sheets and located in a line parallel to said wall, said recesses and posts being so located as to provide a plane interior surface for said car substantially as described.
  25. 3. In a railway car, the combination of walls including metallic sheets, the vertical marginal edges of which are bent to engage with similar edges of an adjacent sheet and 30 to provide a recess at the joint, a vertical rib located intermediate of the edges of the sheets and bent to provide a vertical recess, and wood posts located in said recesses and secured by bolts extending parallel to the 35 plane of the wall, substantially as described.
  40. 4. In a railway car, the combination of walls composed of metallic sheets, the vertical marginal edges of which are bent to provide channels, the channel of one sheet being 45 mounted within a corresponding channel of an adjacent sheet, wood posts mounted in the channel thus formed, and securing means therefor, substantially as described.
  45. 5. In a railway car, the combination of 50 walls composed of metallic sheets, the vertical marginal edges of which are bent to provide channels, the channel of one sheet
- being mounted within a corresponding channel of an adjacent sheet, wood posts mounted in the channel thus formed, and securing means therefor, said securing means extending parallel to the plane of the wall, substantially as described. 55
6. In a railway car, the combination of side and end walls, floor and roof, all composed of metallic sheets, the marginal edges of which are crimped and secured together to provide channels at the intersection of adjacent sheets and wooden strips located in said channels, substantially as described. 60
7. In a railway car, the combination of exterior metallic walls including sheets having flanged vertical edges, the flanges of adjacent sheets being secured together to provide for a vertical channel, a wood post 65 mounted in said channel, securing means passing through said flanges and said post in a line parallel to the wall, and a wood sheathing secured to said post, substantially as described. 70
75. 8. In a railway car, the combination of walls composed of flanged sheets, adjacent sheets being secured together to provide a vertical channel, a wood post in said channel, said post projecting inwardly beyond the plane of the sheets, and a wood lining secured to said post, a space being left between said wood and metallic sheathing, substantially as described. 80
85. 9. A sheet for car sides having its marginal edges bent at right angles to the plane of the sheet to form flanges, the side and bottom flanges being adapted to overlap corresponding flanges on an adjacent sheet, substantially as described. 90
10. A car having paneled walls, the panels being composed of metal sheets bent at their side margins, the bent portions of adjacent sheets providing vertical channels, and strengthening ribs connecting the said 95 channels at the top and bottom thereof, substantially as described.

Signed at Chicago, in the county of Cook and State of Illinois, this 22nd day of May, 1914.
